US00D912046S

(12) **United States Design Patent** (10) Patent No.: **US D912,046 S**
Huang et al. (45) Date of Patent: ** Mar. 2, 2021

(54) **COMPUTING BOX**

(71) Applicant: **Beijing Unicorn Technology Co., Ltd,**
Beijing (CN)

(72) Inventors: **Xi Huang**, Beijing (CN); **Yue He**,
Beijing (CN); **Yue Wang**, Beijing (CN);
Zhihao Zhao, Beijing (CN); **Liwei**
Chen, Beijing (CN); **Jun Wang**,
Beijing (CN)

(73) Assignee: **Beijing Unicorn Technology Co., Ltd,**
Beijing (CN)

(**) Term: **15 Years**

(21) Appl. No.: **29/678,829**

(22) Filed: **Jan. 31, 2019**

(30) **Foreign Application Priority Data**

Dec. 29, 2018 (CN) 201830770670.0

(51) LOC (13) Cl. **14-02**

(52) U.S. Cl.

USPC **D14/358**; D14/300

(58) **Field of Classification Search**

USPC D14/300-301, 348, 355-356, 363,
D14/357-358, 167, 172, 204;
361/679.31; 206/706-709; D9/424-430,
D9/432-433; D10/40, 70; D3/315-316;
D13/103, 107

CPC H05K 5/03; H01L 21/00; H01R 33/92;
H01R 13/057; H04W 88/00

See application file for complete search history.

(57) **CLAIM**

The ornamental design for a computing box, as shown and described.

DESCRIPTION

FIG. 1 is a bottom rear perspective view of a computing box showing our new design;

FIG. 2 is a bottom front right perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines represent portions of the computing box that form no part of the claimed design.

1 Claim, 4 Drawing Sheets
